UNITED STATES PATENT OFFICE.

ROBERT P. GRANT, OF HARTFORD, CONNECTICUT.

BELT.

1,093,263.

Specification of Letters Patent. Patented Apr. 14, 1914.

Application filed December 20, 1912. Serial No. 737,845.

To all whom it may concern:

Be it known that I, ROBERT P. GRANT, a citizen of the United States, and a resident of Hartford, in the county of Hartford and State of Connecticut, have invented certain new and useful Improvements in Belts, of which the following is a specification.

In connection with various laundry machines feeding aprons or belts are utilized to carry the work from one machine to another as for instance, the transferring of the work to a mangle. Heretofore it has been the practice to use aprons in the form of a single wide band, but it is found difficult to force such an apron to run straight and true owing to uneven stretching or tension, with the result that the aprons were soon worn out and constituted a heavy item of expense in the upkeep of the machines. In some cases a number of narrow apron bands have been substituted for the single broad apron, these bands having been made in a strip and their edges joined together. Such bands very soon tear at the joint and are also an item of considerable expense.

It is the object of my invention to produce an endless woven apron band.

Such a band is shown in the drawings, Figure 1 being a general perspective view, and Fig. 2 is a transverse section on an enlarged scale to illustrate the relative thickness of the face and back of the belt.

As seen from the drawing the band made in accordance with my invention is of double thickness, the face being of heavy material, giving strength and wearing qualities, and the back being of lighter material, giving stiffness and weight.

The method of manufacture is as follows:—The tubular form is given in the weaving, and assuming that the band is to be 3 inches in width, I weave first an inch and a half strip of the lighter material for the back, then a three inch strip as A of the heavy material for the face, then a three inch strip of the lighter material, and then alternate with three inch strips of heavy and

light. A length of the goods made in this way is then cut at the middle of the strips of light material, which gives a three inch width of the heavy face and at each edge an inch and a half of the light back. These $1\frac{1}{2}$ inch strips as B are folded in against the underside of the facing and the edges joined together and stitched through the facing as C. I also place a row of stitching as D along the edges of the band, these stitches going through the face and the back. They stiffen and strengthen the web at the edges, and with the central row of stitching, securely unite the face and back of the band. The facing A being of the heavy material will stand the wear to which the surfaces of these bands are subjected, and the light back, while not subjected to the same kind of wear as the face, still gives strength and stiffness and body to the bands. The essential thing is that in this way I am able to produce a band which is endless and properly strengthened to give it a maximum of resisting qualities.

While I prefer to make the facing of heavier material than the back, still I do not wish to be understood as being limited to this precise construction.

I claim as my invention:

A two-ply belt comprising an endless band of woven fabric having a face portion and a back portion in superposed relation, face portion being of relatively greater thickness than the back portion, the back formed of strips integral with the longitudinal edges of the face and each of substantially half the width of the face, said strips folded against the face and having their meeting edges secured together, said strips being also secured to the face both at their meeting edges and at the outer edges of the face and back.

ROBERT P. GRANT.
